UNITED STATES PATENT OFFICE.

JAMES THOMAS ALEXANDER ROSEMERGEY, OF CALUMET, MICHIGAN, ASSIGNOR OF ONE-HALF TO JAMES ROSEMERGEY, SR., OF CALUMET, MICHIGAN.

ADVERTISING DEVICE.

No. 898,993.

Specification of Letters Patent. Patented Sept. 15, 1908.

Application filed October 24, 1907. Serial No. 399,014.

To all whom it may concern:

Be it known that I, JAMES THOMAS ALEXANDER ROSEMERGEY, a citizen of the United States of America, residing at Calumet, in the county of Houghton and State of Michigan, have invented new and useful Improvements in Advertising Devices, of which the following is a specification.

This invention relates to an improved advertising device including, in combination, a calendar and a holder for spools of thread, needles and pins, thimbles, scissors and other like articles which it is desired to keep safely and at the same time conspicuously for immediate use; and the object of the invention is to simplify and improve the construction and operation of this class of devices.

With these and other ends in view, which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications within the scope of the claims may be resorted to when desired.

In the drawing,—Figure 1 is a front elevation of a device constructed in accordance with the invention. Fig. 2 is a side view of the same. Fig. 3 is a perspective detail view of one of the supporting hooks used in connection with the invention.

Corresponding parts in the several figures are denoted by like characters of reference.

The base or body of the improved device is formed by a flat card or board 1 of suitable dimensions and which may be of rectangular shape, as shown in the drawing, although said card or base board may be of any desired ornamental shape or form. Securely mounted transversely upon the base 1 is a plurality of forward extending brackets 2, 2 provided at their front ends with upward extending arms 3 upon which a row of spools 4 may be supported. The brackets 2, which are preferably made of sheet metal, are provided at their rear ends with downturned hooks 5 extending through the base and en-

gaging the rear side of the latter, thus maintaining the brackets in an approximately horizontal and the spool-supporting arms 3 in approximately vertical position. The arms 3 are formed by coiling the upward terminal extensions of the brackets in tubular form, as shown, thus constituting spindles upon which the spools may be supported in such a manner that they will rotate freely when thread is drawn therefrom; the brackets 2 may be provided with apertures 6 registering with the tubular arms 3, and the free ends of the thread upon the spools may be guided through said arms and apertures, as will be clearly seen in Fig. 2 of the drawings, thus preventing the loose ends of the thread from becoming tangled.

Pads or cushions 7 for holding needles and pins are suitably secured upon the base below the row of spool-holding brackets and loops 8 in which thimbles 9 may be supported and are mounted between the pads or cushions 7. Near the lower corners of the base are secured double hooks 10 upon which pairs of scissors 11 may be suspended or supported without danger of opening or spreading; a similar double hook 12 has been shown arranged below the thimble-supporting loops 8, and said double hook 12 may be utilized for an additional pair of scissors or for any other purpose; thus, for instance, a lead pencil 13 might be appropriately supported upon the said double hook. The monthly leaves of a calendar 14 are stapled or otherwise secured upon the base intermediate the hooks 10 and below the hook 12.

The space on the base between the row of spool-supporting brackets and the upper edge of the base is reserved for advertising purposes, as shown at 15; advertising matter of any suitable nature being printed, inscribed upon or otherwise suitably applied to said space. A suspending loop or ribbon 16 is suitably attached to the base adjacent to the upper edge of the latter.

From the foregoing description, taken in connection with the drawing hereto annexed, the operation and advantages of the invention will be readily understood. The construction is simple and inexpensive, and the device when completed forms an extremely convenient and valuable work companion and calendar which, while doubtless especially useful for ladies, will be equally appre-

ciated by men. The device is of such a nature that it may be constructed at a cost which will enable it to be distributed gratuitously for advertising purposes; the device 5 being sufficiently useful to insure its being carefully kept in a majority of cases, unlike ordinary advertising devices, which, as a rule, are quickly destroyed. It is obvious that the value of an advertising medium depends largely upon its being safeguarded and exposed conspicuously to view for a considerable period; and the intrinsic value of the present device is such as to insure its being kept and safeguarded in a majority of instances, as above set forth.

It is obvious that when the device is presented for advertising purposes it is not necessarily accompanied by the outfit of thread, scissors and other appurtenances, 20 this being obviously left to the discretion of the user; it is thought, however, that the cost of the device even when completely fitted out, will not be prohibitive.

Having thus described the invention, what 25 is claimed as new, is:—

1. In a device of the class described, a spool supporting member, consisting of a bracket having a supporting hook and an upward extending tubular spool-supporting 30 arm, said bracket being provided with a

thread-guiding aperture at the lower end of the tubular arm.

2. In a device of the class described, the combination with a base board of a spool supporting member consisting of a bracket 35 formed of sheet metal and provided at its rear end with a downturned hook extending through the base and engaging the rear side of the latter, said bracket being provided adjacent to its front end with an upward extension coiled to form a tubular arm upon which a spool may be supported for rotation.

3. In a device of the class described, the combination with a base-board, of a spool supporting member consisting of a bracket 45 provided at its rear end with a downturned hook extending through the base and engaging the rear side of the latter, said bracket being provided adjacent to its front end with an upward extension coiled to form a tubular 50 spool-supporting arm, and with a thread-guiding aperture registering with the lower end of said arm.

In testimony whereof I affix my signature in presence of two witnesses.

JAMES THOMAS ALEXANDER ROSEMERGEY.
